UNITED STATES PATENT OFFICE.

ANDREW L. BELL, OF BUFFALO, NEW YORK, AND FRANK A. BROWNE, OF WAYNE, PENNSYLVANIA, ASSIGNORS TO THE BARBER ASPHALT COMPANY, OF PHILADELPHIA, PENNSYLVANIA, A CORPORATION OF WEST VIRGINIA.

DEVICE FOR FASTENING ROOFING SHINGLES.

Application filed February 23, 1923. Serial No. 620,711.

To all whom it may concern:

Be it known that we, ANDREW L. BELL and FRANK A. BROWNE, citizens of the United States, residing at Buffalo, in the county of Erie and State of New York, and Wayne, in the county of Delaware and State of Pennsylvania, have invented certain new and useful Improvements in Devices for Fastening Roofing Shingles, of which the following is a specification, reference being had to the accompanying drawings.

Our invention relates to devices more especially useful in fastening so called "prepared" shingles, to the surfaces of roof structures designed for their support. Such shingles ordinarily consist of a base of felt or paper usually impregnated with a suitable water-proof preservative and coated on one or both sides with a weather resistant compound of asphaltum or the like. On account of the comparative lightness of the shingle material and a certain degree of inherent flexibility, the exposed or projecting ends of the shingles, after being laid in the usual way heretofore, were, under windy weather conditions, often lifted to an extent sufficient to cause dislodgment or tearing of the shingles. On the other hand, warping or curling of the projecting shingle ends through direct exposure to extreme changes of temperature, resulted in a condition quite as unsatisfactory, greatly marring the appearance of the roof. These conditions were specially true in instances where the shingles were laid diagonally and consequently with comparatively greater areas of their surfaces exposed.

The main object of our invention is to overcome the various difficulties above pointed out, and this desideratum we attain in a fastening device capable of positively holding and retaining the depending tip or butt end of a diagonally placed shingle of one course, and having incorporated means whereby it may be anchored to the supporting structure of the roof, and, at the same time, serve to secure contiguous corners of adjacent shingles of an underlying or adjacent course.

Other objects and attendant advantages of our invention will become readily apparent from the detailed description which follows of a number of different forms in which our invention is capable of embodiment;

while its scope is as readily deductible from the appended claims.

In the drawings, Fig. I illustrates a fragment of a roof with the shingles placed in diagonal relation, and showing the manner in which our improved fastening device is used.

Fig. II is a perspective view, on a larger scale, of the fastening device in its simplest form, and showing in dotted lines, slight configurative variations; and

Figs. III and IV are views similar to Fig. II, showing other possible modifications of the device.

The simplest form of our invention shown in Fig. II and indicated comprehensively by the numeral 1, may be briefly described as preferably formed of a single piece of stout wire and as comprising a cross bar 2 with laterally extending flanks 3—3 which terminate in perpendicularly disposed prongs 4—4. These prongs are sharpened as by chamfering as indicated at 5, 5, so that they may be readily driven into the supporting structure of a roof in a manner to be presently explained. If desired, in meeting the exigencies of practice, the flanks 3—3 may be disposed either in acute or obtuse angular relation to the cross bar 2 as suggested in dotted lines instead of in the right angular relation illustrated in full.

In building a roof, the shingles indicated by the letter S in Fig. I, are laid a course at a time in a diagonal placement with lateral corners of adjacent shingles in close proximity or abutting as shown in said figure. Either after laying each course, or incidentally to the laying of the individual shingles, a fastening device 1 is, in accordance with our invention, employed to secure the contiguous lateral corners of each adjacent pair of shingles, the prongs 4 being driven through the shingle and into the supporting structure of the roof in a manner obvious from the illustration. This may be accomplished by any type of tool suitable to the purpose, an ordinary hammer serving very well in lieu of any other. After one course of shingles has been laid and fastened in the manner just described, a succeeding course is superposed upon the first, the depending tips or butt ends of the shingles being engaged beneath the horizontally disposed cross bars 2 of the fastening devices 1 before

being in their turn secured as already understood. The fastening devices of our invention therefore not only hold or retain the depending tips or corners of the shingles 5 against displacement, but serve in the additional capacity of securing the shingles of an underlying or subjacent course to the supporting structure of the roof. It is to be especially observed that only the cross bars 10 2 of the fastening devices are exposed, while all other portions are overlapped, so that the possibility of water entering the pierced regions of the shingles is entirely precluded.

The fastening device of Fig. III differs 15 from the previous one only in the flattening of the flanks 3-3 at the region of their emergence with the prongs 4, 4 as indicated at 6, 6. This provision affords heads of expanded area for greater contact with the 20 shingle surfaces and at the same time facilitates driving.

The last modification shown in Fig. IV is 25 identical with the form of Fig. I except for a slight raising or offsetting of the cross bar relative to the plane of the flanks 3-3 to compensate for the thickness of the shingle corner or tip which is to be engaged beneath the same, and to allow the flanks 3, 3 to rest directly and securely against the surfaces 30 of the shingles which are penetrated by the prongs 4-4. This variation may be attained by an additional bending of the wire of the fastening device as indicated at 7-7. Obviously, if desired, either or both the features 35 characterizing the modifications of Figs. III and IV may be incorporated in the type shown in Fig. I.

Strip shingles notched to simulate shingle ends, may obviously be secured and their exposed tips or ends engaged for retainment 40 in a manner similar to that herein-described in connection with the laying of separate or

individual shingles, the advantages procurable being identical.

Having thus described our invention, we 45 claim:

1. As a new article of manufacture, a shingle fastening device comprising a horizontal cross-bar adapted to overlie the butt end of a diagonally placed shingle, declined 50 flanks extending laterally beyond the ends of said cross-bar to compensate for the thickness of the shingle; and said flanks terminating with vertically directed prongs adapted to be secured to the supporting 55 structure.

2. As a new article of manufacture, a shingle fastening device comprising a horizontal cross-bar adapted to overlie the butt end of diagonally laid shingles, flanks extending laterally from the ends of said cross-bar in a slightly depressed plane to compensate for the thickness of the shingle and adapted to be concealed beneath the latter, and prongs integral with the free ends of said flanks whereby the device is secured to the supporting structure. 60

In testimony whereof, I, the said ANDREW L. BELL, have hereunto signed my name at Buffalo, New York, this fifth day of February, 1923. 65
